UNITED STATES PATENT OFFICE.

ALBERTUS TRAVIS, OF JOHNSTOWN, NEW YORK.

CLUTCH.

1,239,985.

Specification of Letters Patent. Patented Sept. 11, 1917.

Application filed May 24, 1916. Serial No. 99,623.

To all whom it may concern:

Be it known that I, ALBERTUS TRAVIS, a citizen of the United States, residing at Johnstown, in the county of Fulton and 5 State of New York, have invented a new and useful Clutch, of which the following is a specification.

This invention relates to clutches particularly designed for use in connection with 10 fleshing machines, one of the objects being to provide a clutch of novel form for automatically uncoupling the driven mechanism from the drive mechanism after a predetermined movement of the driven mechanism.

15 A further object is to provide a clutch which is simple and compact in construction and will not get out of order readily.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, can be made within the scope of what is claimed, without departing from the spirit of the invention.

In the accompanying drawings the preferred form of the invention has been shown.

30 In said drawings:—

Figure 1 is an end elevation of the machine.

Fig. 2 is a rear elevation thereof.

35 Fig. 3 is a section on line A—B Fig. 2.

Fig. 4 is an enlarged inner elevation of the clutch.

40 Fig. 5 is a detail view of the feed nut of the sharpening mechanism and of its restraining means.

Fig. 6 is a detail view of a modified form of roller shifting cam.

Fig. 7 is a central horizontal section 45 through the structure shown in Fig. 4.

Referring to the figures by characters of reference 1 designates a supporting frame with upwardly extending side portions 2 in which are journaled trunnions 3 extending from the ends of a flesher 4 in the 50 form of a cylinder provided, on its periphery, with spiral blades 4 diverging from the center of the cylinder. In other words, the blades upon one half of the cylinder are pitched oppositely to the blades upon 55 the other half, certain of the blades coming together at the center of the cylinder to

form V-shaped knives or scrapers. This has been clearly shown in Fig. 2. A pulley 5 is secured to one of the trunnions 3 and secured to the other trunnion are fixed and 60 loose pulleys 6 and 7 respectively.

Pulley 5 is adapted to transmit motion through a crossed belt 8 to a pulley 9 mounted for rotation on a fixed shaft 10, this pulley 9 being secured to a sleeve 11 revoluble 65 on shaft 10 and to which sleeve is secured a small pulley 12. Motion is transmitted from pulley 12 through a belt 13 to a large pulley 14 supported by a shaft 15 extending transversely of and supported by the rear 70 portion of the frame and which shaft is coupled to the shaft 10 by a link 16. Pulley 14 has a hub 17 constituting an extension and formed with or secured to this hub is a pulley 18 the inner side of which is re- 75cessed as at 19, the wall of the recess being toothed as at 20. Secured to the shaft 15 so as to work within the recess 19 is an arm 21 to which a pawl 22 is pivotally connected, there being a spring 23 interposed between 80 this pawl and a lug 24 on shaft 15, this spring serving to hold the pawl normally pressed outwardly against the toothed wall of recess 19. Extending from the frame 1 is an arm 25 having a laterally extending 85 finger 26 constituting a guide for a clutch member 27 which is slidably mounted on but does not rotate with the shaft 15. This clutch member includes oppositely extending arms 28 one of which has a forked terminal 29 which slidably engages the finger 26. Parallel stripping pins 30 project from the respective arms 28 of the clutch member and extend into the recess 19 where they will be successively engaged by the pawl 22 90 during the rotation of shaft 15. Clutch member 27 is engaged by a yoke 31 at the upper end of an arm 32 which is secured to a rock shaft 33 on one side of the frame 1. This rock shaft has a foot lever 34 attached to the front end thereof and which is normally yieldingly supported by a spring 35.

The hub 17 has a sprocket 36 designed to transmit motion through a chain 37 to a 105 sprocket 38 secured to one end of a shaft 39 which is journaled in spring pressed bearings located in the upper portions of the sides of frame 1. To this shaft 39 is secured a corrugated roller 40 which co-operates with another roller 41 preferably of rubber. This roller 41 is secured to a shaft 110

42 journaled in bearings 43 carried by the upper ends of arms 44. These arms are fulcrumed upon studs 45 extending inwardly from the sides of the frame 1. The arms are extended downwardly and rearwardly from their fulcrums and are provided at their lower ends with anti-friction rollers 46 constantly engaging cams 47 secured to and revoluble with the shaft 15. A gear 48 is secured to shaft 37 close to one end of roller 40 and another gear 49 is secured to shaft 42 adjacent one end of roller 41. These gears 48 and 49 have long teeth so that the two gears will constantly mesh irrespective of any shifting of the roller 41 relative to the roller 40. The parts are so proportioned that when the cams 47 have thrust the rollers 46 downwardly as far as possible, the roll 41 will be pressed against the roll 40 or will be binding tightly upon a hide inserted between the two rolls. Furthermore when the parts are thus located, the roll 41 will be pressed inwardly toward the flesher 4.

25 A chute 50 may be mounted below the flesher and the roll 41 and a hood 51 may be located above the flesher, the same being spaced sufficiently from the roll 40 to permit the insertion of a hide downwardly between the hood and the roll.

For the purpose of keeping the blades of the flesher sharp, two oppositely rotating screws 52 and 53 are arranged across the rear portion of the machine and are journaled in the sides of the frame 1. These screws are provided with meshing gears 54 at one end and a pulley 55 is connected to one of the screws and receives motion through a belt 56 from the pulley 18. A 35 guide rail 57 connects the sides of the frame and is parallel with and in front of the screws 52 and 53. This rail is slidably engaged by a carriage 58 having an arm 59 which is designed to travel along the back 45 or outer face of the rail 57 and has a stem 60 slidably mounted therein. A foot 61 is provided at the inner end of this stem and a head 62 is provided at the outer end. A spring 63 is mounted in the arm and bears 50 against the foot 61 and serves to hold said foot normally pressed into engagement with a finger 64 extending from the center of a feed nut 65. This feed nut is pivotally mounted within the carriage upon a pin 66 55 provided therefor and includes oppositely extending threaded yokes 67 and 68. The yoke 67 is designed to engage the upper feed screw 52, while the lower yoke 68 is designed to engage the feed screw 53. Finger 64 has faces 69 which converge to a point and when one of these faces is engaged by the foot 61, yoke 67 will be pressed against the feed screw 52. When the other face 69 is 60 engaged by the foot 61, yoke 68 will be 65 pressed into engagement with the feed screw

53. When the point of the finger is engaged by the foot 61, both yokes 67 and 68 will be held out of engagement with their feed screws. When the nut is in this position the carriage can be shifted freely along the 70 guide rail.

Slidably mounted on the carriage is a holder 70 to which is secured a block 71 of sharpening material such as emery. This holder is engaged by an adjusting screw 72 75 swiveled in the carriage and it will thus be seen that by manipulating this screw the sharpening block can be shifted toward or from the path of movement of the active edges of the flesher blades.

If desired, and as shown in Fig. 2, deflecting fingers 73 and 74 may be extended toward each other from the ends of the screws, the finger 73 being designed to engage the finger 64 and deflect it downwardly from the position shown in Fig. 5 or from its raised position, while the finger 74 is designed to engage finger 64 and deflect it upwardly to bring the yoke 67 into engagement with the screw 52.

In using the apparatus the flesher is rotated by a belt, not shown, engaging the fixed pulley 6 and the blades of the flesher will thus rotate in the direction indicated by the arrow in Fig. 3. At the same time motion will be transmitted through the belt 8 to pulleys 9 and 11, thence through belt 13 to the pulley 14 which will be caused to rotate in the direction indicated in Fig. 1. As the pulley 18 rotates with pulley 14, motion will be transmitted through belt 56 to the feed screws 52 and 53 and motion will also be transmitted through the chain 37 to the upper feed roll 40 which, by means of gears 48 and 49, transmits motion to the 100 lower feed roll 41, the two feed rolls rotating in the direction indicated by the arrows in Fig. 3. If the yokes 67 and 68 of the nut 65 are out of engagement with the screws 52 and 53, the transmission of motion through 105 the said screws will have no effect.

While the parts are operating as described, the foot lever 34 will be in its normal or raised position.

Thus the stems 30 will be pressed into the 115 recess 19 and one of them will be engaged by the pawl 22, thus holding said pawl disengaged from the teeth 20 and allowing pulley 18 to rotate freely on the shaft 15. Assuming that the cams 47 are extended upwardly 120 at this time, they will move the arms 44 with their upper ends lowered so that the lower feed roll 41 will be moved downwardly and outwardly away from the flesher. By inserting a hide between the rolls 40 and 41 125 so that the flesh side of the hide will be toward the flesher 4, and by then momentarily depressing the lever 34, the pins 30 will be withdrawn from the recess 19, thus allowing pawl 22 to spring outwardly 130

into engagement with one of the teeth 20. Consequently the rotating pulley 18 will also transmit motion through the pawl 22 and arm 21 to the shaft 15 and cause the cams 49 5 to rotate. Upon the completion of a one-half revolution, the pawl 22 will come into contact with the other pin 30 which has moved back into the recess 19 as soon as the foot lever has been released and, consequently, the pawl will be disengaged from the tooth 20 so that the rotation of the cam 47 will cease while the pulley 18 will continue to rotate. This one half rotation of the cam will be enough to swing the roll 41 10 backwardly and upwardly toward the flesher so that as the rapidly rotating flesher operates to remove the membrane, etc., from the hide, the edge of the hide will be gripped between the feed rolls 40 and 41 and will be withdrawn from the machine slowly. The substances removed from the hide will be thrown downwardly onto the chute 50. As soon as the hide has passed through the machine the foot lever can be momentarily 15 depressed to release the pawl 22, thus allowing shaft 15 to make another one half revolution whereupon the pawl will come against the other pin 30 which has moved back into the recess 19 with the result that the pulley 20 25 30 35 40 45 18 will be automatically uncoupled from the shaft and the cams will remain stationary after permitting the arms 44 to shift so as to swing the roll 41 away from the flesher. Should it be desired to sharpen the blades of the flesher while the machine is in operation, it would merely be necessary to tilt the nut 65 out of the position shown in Fig. 5 so that, for example, yoke 67 will engage the screw 52. This screw, which is constantly rotating, will carry the nut and the carriage longitudinally along the rail 57 and by adjusting the sharpening material 71 toward the flesher, the edges of the blades will be brought successively into engagement there-

with as said block is fed transversely of the machine. By shifting the nut in the opposite direction, the block can be returned to its initial position or, if desired, this shifting can be effected automatically by the fingers 50 55 73. In other words, when the nut 65 reaches one limit of its movement, the finger 64 will engage finger 73 and be thrown downwardly to bring yoke 68 into engagement with screw 53 whereupon the carriage will be moved 60 back toward its initial position until the finger 64 engages finger 74 which will throw the nut upwardly and bring the yoke 67 again in engagement with screw 52. Thus the sharpening means will move back and forth slowly and throughout the length of the flesher. The sharpening operation can take place either during the fleshing operation or after such operation.

As shown in Fig. 6 a cam 75 may be used 65 in lieu of the cam 47. This cam 75 has its periphery so shaped at 76 that a partial rotation of the cam can be effected without moving the arm 44 and the parts connected thereto. 70

What is claimed is:—

In combination, a normally stationary clutch member including a spring pressed pawl, a normally revoluble clutch member having teeth for engagement by the pawl, 75 means normally in the path of the pawl for holding the clutch members disengaged, means for momentarily releasing the pawl to couple the clutch members and cause the same to rotate in unison, said pawl engaging means operating to automatically disengage the clutch members upon the completion of a one-half revolution of the members. 80

In testimony that I claim the foregoing as my own, I have hereto affixed my signature in the presence of two witnesses. 85

ALBERTUS TRAVIS.
